UNITED STATES PATENT OFFICE.

PIERRE P. GILLES, OF SPRINGFIELD, MASSACHUSETTS.

CARBURETOR.

Application filed August 7, 1918, Serial No. 248,697. Renewed March 24, 1922. Serial No. 546,491.

To all whom it may concern:

- Be it known that I, PIERRE P. GILLES, born in Switzerland of German parentage, now believing myself to be a citizen of the 5 Swiss Confederation, and having formally declared my intentions of becoming a citizen of the United States of America in conformance with the United States immigration laws, and now residing at Springfield, 10 in the county of Hampden and State of Massachusetts, United States of America, have invented certain new and useful Improvements in Carburetors, of which the following is a specification.
- 15 This invention relates to carburetors and more particularly to improvements which are designed to render carburetors more suitable for use in vehicles which are driven at high speeds.
- 20 It is now well-known that with a single spray nozzle the proportions of fuel and air in the fuel mixture vary for different engine speeds, the ratio of fuel to air being higher for high than for slow engine speeds.
- 25 To remedy this difficulty, the compound nozzle has been proposed in which an additional nozzle is provided and arranged to deliver proportionately more fuel at low than at high engine speeds. The two nozzles thus 30 work in compensatory relation to the end that a substantially constant ratio between the constituents of the fuel mixture is approximated over a wide range of engine speeds.
- 35 It has been my experience, however, that, while the compound nozzle works satisfactorily for average speeds, as, for example, up to thirty-five miles per hour or thereabouts in automobiles, it delivers an over-
- 40 rich mixture when the vehicle is run at the higher speeds as, for example, from forty to sixty miles per hour. This invention is concerned among other things with the provision of means to improve the ratio of the 45 fuel constituents at high engine speeds and to make this improvement without altering the construction and design of the compound nozzle which has proved satisfactory for average engine speeds.
- 50 The invention has for an object to provide in combination with the compound nozzle of a carburetor, a choke tube adjacent the nozzle, which tube is expandable from an opening of a predetermined size to another opening of predetermined size throughout a limited range and is so constructed as to be

held normally to its smaller and more restricted opening, but is movable when a predetermined engine speed is exceeded to enlarge the opening. 60

According to this object, after a certain engine speed has been exceeded and at about the time when the fuel mixture tends to become too rich, the choke tube expands, by the increased suction and increased velocity 65 of the inrushing air, to diminish the suction so that less fuel is drawn from the compound nozzle. Thus, the expandible choke tube comes into play, when needed, as a supplementary regulating means for the 70 fuel flow, which means combines with the compound nozzle by contributing to the same general result aimed at by the provision of the compound nozzle. 75

Another object of the invention is to provide in combination with a carburetor of the type described, means to automatically supply fuel to the carburetor by the suction produced in the intake pipe of the carburetor, such means including a valve to open 80 and close the fuel suction connection to the intake pipe and vary the degree of opening proportionately with the variations of the opening of the intake pipe by the throttle, such means being particularly characterized 85 by the provision of means which are operable independently of the position of the throttle to open the valve when, for any given throttle opening, the suction becomes insufficient due to slackened engine speed. 90

According to this object when, for example, the engine is running at high speed with a full throttle opening and slackens in speed due to travel of the automobile on a steep upgrade, more fuel may be supplied to the 95 carburetor by providing an increased area upon which the suction, although decreased in degree, may act so that the supply of fuel in the carburetor is maintained at the time when the maintenance of such supply is of 100 the highest importance. In this connection, it is to be noted that the expandible choke tube in addition to its primary function may, under the described contingency, contract and thus aid in supplying increased 105 fuel at this time while ordinarily it tends to reduce the fuel supplied to the engine. The improved valve arrangement for controlling the fuel supplied to the carburetor thus contributes to the work accomplished 110 by the expandible choke tube.

Other objects and advantages will appear

in the following description and will be pointed out in the appended claims.

The invention, in an embodiment at present preferred, is disclosed for illustrative purposes in the accompanying drawings, in which—

Fig. 1 is a top plan view of a carburetor embodying the invention;

Fig. 2 is a sectional elevational view thereof taken on the line 2—2 of Fig. 1;

Fig. 3 is a cross-sectional view taken on the line 3—3 of Fig. 1;

Fig. 4 is a sectional plan view taken on the line 4—4 of Fig. 3;

Fig. 5 is a sectional elevational view taken on the line 5—5 of Fig. 1;

Fig. 6 is an enlarged sectional view of the compound nozzle of the carburetor;

Fig. 7 is a sectional plan view taken on the line 7—7 of Fig. 6;

Fig. 8 is a fragmentary sectional plan view taken on the line 8—8 of Fig. 5;

Fig. 9 is a fragmentary sectional elevational view taken on the line 9—9 of Fig. 1;

Fig. 10 is a fragmentary sectional view which is taken similarly to Fig. 2 and shows a modification in one feature of the invention; and

Fig. 11 is a cross-sectional view taken on the line 11—11 of Fig. 10.

Referring to these drawings, the carburetor casing, indicated generally by reference letter A, is formed with two main chambers 12 and 13, (Fig. 4) arranged side by side in adjacent relation, and a substantially horizontally disposed air intake pipe 14 which as indicated in Fig. 2, passes through the chamber 12. The casing A may be suitably made up, preferably for convenience in several sections held together by bolts 15 (Figs. 1 and 3), to provide leak-proof chambers, and the chamber fuel supply 13 is also made airtight by a suitable permanent cover member 16. The chamber 12 is also closed at its upper end by a cover 17 (Fig. 2) pivoted to the cover member 16 and arranged to permit convenient access to the chamber 12. The latter is not sealed by cover 17, and air is purposely allowed to enter therein, as by a suitably screened opening 18 (Fig. 2).

Chamber 12 constitutes the carburetor fuel chamber from which fuel is drawn into the suction pipe 14 through suitable atomizing devices. The atomizing devices are of the compound type, which involve main and compensating nozzles. Both these nozzles are contained in a sleeve 19 (Fig. 2) which passes vertically downwardly through the pipe 14 and into a hollow tubular portion 20 of the casing 10. The sleeve 19 has a lower portion 21 of reduced diameter, whereby a shoulder 22 is formed to seat on a corresponding shoulder formed in the interior bore of member 20 and the sleeve 19 and its lower portion 21 closely

fit the bore of member 20 to prevent the passage of fuel therebetween. Fuel is supplied from chamber 12 into the base of the tubular member 20 by way of passages 23 and 24 (Fig. 2). Fuel is also supplied from chamber 12 through an opening 25 (Fig. 9) regulable by a needle valve 26, into a passage 27 and thence into an annular groove 28 in member 20.

The main nozzle consists of a tube 29 (Fig. 6) threaded into sleeve 19 from below and having an axial passage 30 through which fuel from the base of member 20 may be drawn by suction and delivered through openings 31 in the wall of sleeve 19 into the pipe 14. The delivery opening of the main nozzle is regulable by a needle valve 32, threaded into the upper end of and depending into sleeve 19 into cooperative relation with the upper end of passage 30. The tube 29 is necked down intermediate its ends to afford an annular passage 33 between it and the sleeve, and such passage communicates by means of a hole 34 in the reduced portion 21, with the described groove 28 in member 20. The upper end of tube 29 is squared, as shown in Fig. 7, to afford openings 35 through which fuel from passage 33 may be drawn and delivered by way of openings 31 into pipe 14. The passage 33 constitutes the compensating nozzle of the carburetor.

Fixed at one end in the air intake pipe 14 is a choke tube 37 (Fig. 2) which, except for its fixed end, is composed of a plurality of thin spring fingers 38. The described sleeve 19 passes loosely through two of these fingers and is disposed closely adjacent the restricted portion of the choke tube. The free ends of fingers 38 are flared outwardly as at 39, and their outer ends are normally slightly spaced from the interior wall of pipe 14. The fingers 38 are so constructed that, with the degree of suction and the velocity of air obtaining in pipe 14 on average engine speeds, they remain in the illustrated position to provide a "choke" of predetermined size for average running conditions. When, however, the degree of suction or the velocity of the inrushing air exceeds a predetermined value, the fingers 38 may yield to the limit prescribed by the abutment of their outer ends with the interior wall of pipe 14. Thus, a "choke" of greater opening, but still of predetermined size, is provided for the higher engine speeds.

The chamber 13 above described is a fuel supply chamber into which fuel may be drawn by suction, for subsequent delivery by gravity flow to the carburetor fuel chamber 12. Referring to Fig. 5, a fuel inlet 40 is provided in the upper portion of chamber 13, and such inlet is adapted to be connected to a low level fuel supply tank. Formed in an upwardly extending boss on cover plate 16 is a passage 41, the upper end thereof being

ing enlarged to receive a ball valve 42 and to form a shoulder 43 on which the valve may seat. The upper end of passage 41 communicates with the atmosphere by way 5 of openings 44 and below shoulder 43 the passage 41 is connected by passages 45 and 46 to the chamber 13, whereby, when ball 42 is held away from its seat, as illustrated, air 10 may enter the chamber 43. Slidable in passage 41 is a rod 47 which may lift ball 42 and hold it lifted as shown. On rod 47 and closely fitting passage 41 is a disc 48 which at all times prevents the passage of air from the upper to the lower portion of passage 15 41, but never closes communication between the upper portion and passage 45. A disc 49, also fixed on rod 47, may seat against the lower face of the cover to prevent communication between chamber 13 and a pipe 20 50 which opens into passage 41 at such a point as to be always below the disc 48. Pipe 50 extends to the upper end of a vertical passage 51 (Figs. 2 and 3), and such passage may communicate with the air intake 25 pipe 14 in a manner to be later described in detail.

It will be seen that, with the parts in the relative positions illustrated in Fig. 5, air 30 may enter chamber 13 while communication between the latter and pipe 14 is prevented. The rod 47, however, may be lowered to a limited extent to allow ball 42 to seat on shoulder 43, and such movement of the rod will carry disc 49 away from its seat, whereby 35 pipe 14 may communicate with chamber 13 and communication between the latter and the atmosphere is prevented. The rod 47 is arranged to be moved sharply from one position to another by mechanism operated from a float 52 in chamber 13. Thus a pair 40 of spaced arms 53 pivoted at 54 to cover plate 16 are pivotally connected to a rod 55 upstanding from float 52. A second pair of spaced arms 56 are loosely mounted on 45 pivot 54 and extend toward the disc 49 and terminate with rounded ends which ride in a circumferential groove 57 formed in the disc. A spring 58 connects the opposite ends of each pair of arms 53 and 56. Thus, when 50 the fuel in chamber 13 falls to a predetermined level, the lowering of float 52 gradually draws arms 53 downwardly, and, as soon as the spring 58 crosses to the lower side of pivot 54, it sharply draws down arms 55 56 and thus rod 47 to the limit defined by the abutment of the rod and a ledge 59 on casing A (Fig. 5). Similarly when the fuel in chamber 13 rises to a predetermined level, the raising of float 52 gradually raises arms 53 and, as soon as spring 58 crosses to the 60 upper side of pivot 54, it sharply raises arms 56 and thus rod 47. Thus, the chamber 13 may alternately be connected to the atmosphere and the air intake pipe 14.

65 The chambers 12 and 13 are provided near

their lower portions with openings 60 and 61, respectively which open into a passage 62 formed on the outer portion of the casing by a removable dish-shaped plate 63, all as shown in Fig. 4. Communication between 70 the chamber 13 and passage 62 is controlled by a check valve 64 which opens into the passage 62, as best shown in Fig. 5.

Referring now to Fig. 2, the described suction passage 51 intersects the air intake 75 pipe 14, but the lower portion of the passage is made of reduced diameter to receive and guide a squared stem 66 of a valve 67 which is adapted to seat against a shoulder 65 formed in passage 51 to prevent communication between the pipes 14 and 50. When valve 67 is raised from its seat, communication between pipes 14 and 50 is permitted by way of the spaces between the squared shank 66 and the circular wall of the passage 51. 80 The head of valve 67 is similarly squared, as indicated, for a like purpose. The valve stem 66 is adapted to be lifted by a cam 68 formed on a throttle valve 69, which is arranged in pipe 14 and adapted to vary the 85 effective opening thereof. Valve 69 is oscillatable by a lever 69' (Figs. 1 and 3) in the usual manner. The cam 68 is constructed to move valve 67 as the throttle valve 69 is moved for the purpose of varying the effective opening of passage 51 proportionately 90 with the variations in the effective opening of pipe 14 by the throttle valve.

The face of cam 68 consists of a curved spring 70 which is secured at one end to the 100 cam at the point thereon of shortest radial distance from the axis of the throttle valve. The spring 70 is so constructed that its free end normally lies a slight distance away from the face of the cam 68 and so that all 105 other points from the free to the fixed end of the spring are also spaced from the cam, but by progressively decreasing distances. The valve stem 66 is held to the cam, or more properly the spring 70, by suction, 110 and the spring is made of such strength that it will be compressed by stem 66, as throttle valve 69 is turned, under the degrees of suction ordinarily obtaining in the intake pipe 14. Normally then the spring 70 acts 115 merely as a facing for the cam 68, but it may, when the suction in pipe 14 falls below a given degree, spring away from the cam, as into the illustrated position, and thereby cause an additional lift of stem 66.

The essential feature of the valve construction described is the provision of a resilient device between the cam 68 and valve 67, and it matters little just where such device is interposed. Thus, as shown in Fig. 10, the valve 67 may have a round stem 71 telescoped into and slidable relatively to, a hollow stem 72, the end of which is arranged to bear on cam 68. The outer portion of stem 72 is of generally square 120

construction (Fig. 11) for the same reason as set forth in connection with the valve stem 66 already described. A spring 73 in stem 72 tends to lift stem 71, but in normal operation is held compressed due to the greater pressure acting on the head of valve 67 than on stem 72. When, however, the suction in pipe 14 falls below a predetermined degree, the spring may lift stem 71 into the illustrated position. A pin 74, passing diametrically through stem 71, has its ends disposed in slots 75 in the wall of stem 72, so that the degree of movement between stems 71 and 72 is limited by the confines of slots 75.

The valve 67 is also made to perform another function. Referring to Fig. 2, above valve 67, an annular ring 76 is fixed in passage 51, and the head of valve 67 may engage ring 76, if the valve 67 is moved beyond the limits prescribed by the throw of cam 68 and the added increment of movement which may occur by reason of the spring 70 or spring 73. Thus, valve 67 may cooperate with ring 76 as a seat to prevent communication between pipes 14 and 50. Thus, upon backfiring, the excessive pressure in pipe 14 will force valve 67 upwardly into engagement with ring 76, and this result is particularly desirable here, since otherwise, backfiring would cause the fuel in chamber 13 to be driven into chamber 12 and flood the carburetor.

In operation, fuel from the low level tank 35 is drawn into chamber 13 by the suction produced in pipe 14, which is effective upon the chamber when valves 67 and 49 are open, by way of the passages 41, 50, and 51. As soon as the fuel in chamber 13 reaches a predetermined level, valve 49 is closed by the rising of float 52 to prevent further exhaustion of chamber 13, and the latter is then connected to the atmosphere by way of passages 45 and 46 and that portion of passage 41 above disc 48, the ball 42 having been lifted free from its seat simultaneously with the closing of valve 49. The fuel in chamber 12 is maintained at the same level as that in chamber 13 by gravity flow through the passage 62, the check valve 64 preventing return flow. The rate at which fuel is drawn into chamber 13 is automatically controlled by the valve 67 which varies the area available for suction to act on the chamber in proportion to the variation of the area of the intake pipe 14.

Such regulation of fuel flow is ordinarily sufficient but in certain instances, as when for any given throttle opening, the speed 60 of the engine slackens materially, the suction may decrease to such a degree that fuel is drawn into chamber 13 at an insufficient rate. At such times, namely, whenever the force acting to hold the valve stem 66 against cam 68 becomes less than that of

spring 70, the latter lifts valve 67 and thus increases the port area through which the air from the chamber 13 is drawn, and this increase in port area increases the rate of flow of fuel into chamber 13. Thus, when the carburetor is used on an automobile and the speed of the latter even with a full throttle opening slackens, as on a grade, the spring 70 or 73 acts and allows fuel to be fed to chamber 13 at an increased rate 75 to compensate for increased flow from chamber 12 through the atomizing devices.

The high speed and compensating nozzles work in compensatory relation in the known way so that under average conditions of 80 running, the ratio of fuel to air is maintained substantially constant. On the very high speeds, however, the fuel mixture tends to become rich due to the high degree of suction created in pipe 14 at high engine 85 speeds. After the suction in pipe 14 exceeds a predetermined degree, the flexible blades 38 are forced outwardly by the force of the inrushing air on their flared ends 39 with the result that the area of the choke 90 tube is increased, and such increased area naturally decreases the velocity of the air adjacent the exit of the nozzles and thus diminishes the flow.

The flexible choke tube also may function at times when the suction in pipe 14 becomes insufficient to draw sufficient fuel from the nozzles to supply the needs of the engine. Thus, if the carburetor is used on an automobile and the latter is travelling 100 at high speed with a full throttle opening, a slackening of engine speed due to the encountering of a grade will cause a decrease in suction, and the flexible blades 38, having previously been in expanded position 105 due to high speed operation as described, will spring into the illustrated position and, by restricting the pipe 14, cause increased suction and increased flow of fuel from the nozzles. The flexible choke tube and springs 110 70 or 73 thus contribute to the same useful end, the latter providing for increased feeding of fuel into the fuel supply chamber 13 to replace the fuel drawn at an increased rate from chamber 12 by reason of the operation of the flexible choke tube in the 115 described manner.

The flexible choke tube thus possesses all the usual advantages of the known variable choke tubes and in addition has an important 120 primary advantage not obtained with the usual variable choke tubes. That is to say, the choke tube in addition to its known functions combines with the main and compensating nozzles to improve and supplement 125 the proportioning of the ingredients of the fuel mixture. The present flexible choke tube is to be distinguished from the usual variable choke tube in that it is arranged to come into play only when the 130

- velocity of the inrushing air has reached a predetermined value. It comes into play only at high speed and after the compound nozzle arrangement fails to satisfactorily 5 regulate the proportions of the constituents of the fuel mixture. At all other times, and for average engine speeds, it provides a restriction of pipe 14 to a predetermined area and is movable at high speeds to a definite 10 limited degree to provide a larger restriction of the pipe but still one of predetermined area.

The invention has been disclosed herein, in an embodiment at present preferred, for 15 the purposes of illustration, but the scope of the invention is to be defined by the appended claims rather than by the foregoing description.

What I claim is—

- 20 1. In a carburetor, an air intake pipe adapted for connection to suction means, a fuel supply chamber adapted for connection to a low level fuel tank, means to deliver fuel from said chamber to the intake pipe, 25 a passage connecting the latter to said chamber, whereby fuel from the low level tank may be drawn by suction to said chamber, a throttle to vary the effective opening of the intake pipe, a valve in said passage operable 30 to vary the effective opening thereof proportionately with the variations of said intake passage by the throttle, and means operable for any given position of the throttle to impart an additional movement to said 35 valve when the suction in said pipe diminishes to a predetermined degree.

2. In a carburetor, an air intake pipe adapted for connection to suction means, a fuel supply chamber adapted for connection to a low level fuel tank, means to deliver fuel from said chamber to the intake pipe, a passage connecting the latter to said chamber, whereby fuel from the low level tank may be drawn by suction to said chamber, a throttle to vary the effective opening of the intake pipe, a valve in said passage 45

operable to vary the effective opening thereof proportionately with the variations of said intake passage by the throttle, and resilient means operable for any given position of the throttle to impart an additional movement to said valve when the suction in said pipe diminishes to a predetermined degree. 50

3. In a carburetor, a suction passage, a valve controlling said passage and normally movable toward closed position by the force due to suction, and means operable to open said valve against the force due to suction, including means operable when the force 60 due to suction decreases to a predetermined degree to move said valve beyond the position to which it is moved by the first-named means.

4. In a carburetor, an air intake pipe 65 adapted for connection to suction means, a throttle to vary the effective opening of said pipe, a passage communicating with the latter and to which suction is to be applied for fuel feeding purposes, a valve movable by 70 the throttle to vary the effective opening of the passage, and resilient means between the valve and throttle operable when the suction in the intake pipe falls below a given degree for any given position of the throttle 75 to impart an additional increment of movement to said valve.

5. In a carburetor, an air intake pipe adapted for connection to suction means, a fuel supply chamber into which fuel may be 80 drawn by suction, means to supply fuel from the chamber to said intake pipe, a suction passage between the chamber and intake pipe, spaced seats provided in said passage, and a valve normally cooperating with one 85 seat to vary the effective opening of the passage and operable when the pressure in the intake pipe exceeds that in said passage to cooperate with the other seat and close the passage.

PIERRE P. GILLES.
